UNITED STATES PATENT OFFICE.

WILLIAM B. COGGER AND HENRY A. HAMLIN, OF MINNEAPOLIS, MINN.

DOOR-HANGER.

SPECIFICATION forming part of Letters Patent No. 357,580, dated February 15, 1887.

Application filed October 4, 1886. Serial No. 215,261. (No model.)

To all whom it may concern:

Be it known that we, WILLIAM B. COGGER and HENRY A. HAMLIN, of Minneapolis, in the county of Hennepin and State of Minnesota, have invented certain new and useful Improvements in Door-Hangers, of which the following is a specification.

Our invention relates to an improvement in anti-friction hangers for sliding doors; and it consists, generally, in constructing a hanger of this description by means of which the point of suspension is brought nearer to the top of the door, economizing in the length of the brackets and suspension-rods. We are also enabled by this means to place the friction-rods closer to the edges of the door, and thus obviate the overhang which is often experienced.

Our invention further consists in the construction and combination hereinafter described, and particularly pointed out in the claims.

In the drawings which form part of this specification, Figure 1 is an elevation of a portion of a door suspended by our improved hangers. Fig. 2 is a longitudinal section of a portion of a door, showing one of the hangers in place. Fig. 3 is a cross-section on line $x-x$ of Fig. 2.

22 represent a line of studding placed in the usual manner on either side of the door 3, and forming a recess into which the door recedes.

4 are inverted-U-shaped brackets securely fastened to both of the opposing studs, and are placed at suitable intervals to support the rails of the track 6, secured to their lower extremities. These brackets both support the rails and also take the place of the usual spacing-blocks between the studs. By this means a uniform spacing of the studs is secured, and both rails of the track, being supported upon the same bracket, will be evenly spaced and always in line with each other. These rails form a guide and support for the flanged wheels 8, and are of sufficient length to allow for the full travel of the door.

The flanged wheels 8 are preferably constructed in pairs and connected by an axle, 9.

10 is a hanger consisting of a plate provided with a slot, 11, which is placed between the

two flanged wheels 8. The axle 9 extends through the slot 11, forms a bearing upon its upper wall, and travels in the slot as the wheel rolls upon the track, thus making an anti-friction bearing. The lower extremity of the plate 10 passes between the rails 6, and is provided with a flange or flanges, 13. The length of the plate 10 from the axle to the flange is preferably such that the distance between the top of the flange 13 and the under side of the rail 6 shall be less than the height of the flange upon the wheels 8, so that when the hanger is in place it will be impossible by any accident to remove the wheels from the track.

Ribs 14 may be constructed between the plate and the flange, for the purpose of strength and stiffness.

15 represents an opening in the plate of the hanger 10 at or near the center of the flange, 70 and the flange at this point may be slightly re-enforced in thickness, for the purpose of strength and to form a bearing for the head of the bolt 17, which passes through it. The hole in the flange for the reception of the bolt 75 is made sufficiently large to allow the bolt to be inserted on a slight angle, to bring the head of the said bolt into the opening 15; but when the bolt is raised in a direct line the head will strike the plate at the top of the opening 15, 80 and thus limit its upward movement.

19 is a bar, preferably a little less in length than the width of the door, to avoid the possibility of the ends of the bars striking each other before the doors are entirely closed. 85 This bar is securely attached at each end to the hangers 10, and is supported thereby. The bolts 17 pass through this bar, and after the said bar is in place it is impossible to give the bolts a sufficient angle to allow the head to 90 pass the plate 10, in the manner above described. They are thus securely retained and the danger of accidental displacement is obviated. The lower end of the bolt 17 is screw-threaded, and above the thread upon the shank 95 of the bolt we prefer to form the hexagon 21. The location of the hexagon is such that it will be in line with the opening or recess between the door 3 and the head jamb-casing 22, as shown in Fig. 3.

100 23 represents metal sockets placed in the upper edge of the door to receive the ends of

the bolts 17, and screw-threaded to correspond with said bolts. The said sockets are let into the upper edge of the door and are secured thereto by suitable screws, as shown.

5 24 are door-stops of the usual form, which serve as a guide and cover the opening between the door and the jamb. One of these stops may be secured to the jamb by screws, to allow it to be readily and easily removed.

10 It will be seen that the hangers must be put in place before the partitions are finished. Usually one row of studs is first put in place.

The rails 6 are preferably formed in two sections. One section is completed and attached to the brackets and the brackets lined and secured to the row of studs. Both trucks, together with their suspending-bolts 17 and bar 19, are now placed upon the section, and afterward the remaining section is lined and secured in a similar manner. After this the other row of studs can be placed. When the door is ready to be hung, it is placed under the bar 19 and in position so that the bolts 17 will drop into the sockets 23. A suitable wrench is now applied to the hexagon 21 upon the said bolt, and by this means it is turned, and, the screw entering the thread in the socket, the door may be raised and properly adjusted. The stops 24 are then put in place, 25 and the work is completed.

If from any cause the door should need re-adjustment, one of the stops can be readily removed and the proper adjustment made.

Some of the advantages of this construction are as follows: The point of suspension of the door is below the wheels and rails, thus making it practical to use short suspension-rods and short brackets. By placing the bar below the track we are enabled to bring the wheels and 30 rails closer together. The two lines of studs may be set nearer each other and the whole partition made thinner. As the friction-rolls are near the edges of the door, there can be no tipping of the door over its point of suspension as it is moved to and fro. The doors may 35 be readily secured to the hangers or removed therefrom, and it is not necessary to mortise

or cut the face of the door to have access to the bolts for the purpose of adjusting them. It is impossible for the wheels to get off of the 50 track or for the suspension-bolts to get out of place after the bar 19 has been put in position.

The rails secured to the bracket in this way are prevented from closing together and pinching on the flanges of the wheels. By this construction the device can be put together and applied to the door by any ordinary mechanic.

We claim as our invention—

1. The combination, with the rails 6 and the flanged wheels 8, of the hanger 10, secured to the axle of said wheels and extending below said rails, and the bar 19, secured to the flange of said hanger, the distance between the under side of the rail and the top of the flange 13 being less than the depth of the flanges of 65 the wheels, substantially as described, and for the purpose set forth.

2. The combination, with the rails and the flanged wheels, of the hanger 10, having the opening 15, the bolt depending from said hanger, and the bar 19, secured to said hanger and having an opening through which said bolt passes, substantially as described, and for the purpose set forth.

3. The combination, with the U-shaped 75 brackets and the rails 6, supported upon said brackets, of the flanged wheels 8, the hanger 10, the bar 19, secured to said hanger below the rails 6, the door, and the suspension-bolts 17, all substantially as described.

4. The combination, in a door-hanger, with the supporting-rails and the flanged wheels upon said rails, of the bar 19, suspended upon the axles of said wheels and arranged beneath said rails, and a suspension-bolt at each end of 85 said bar, substantially as described.

In testimony whereof we have hereunto set our hands this 28th day of September, 1886.

WILLIAM B. COGGER.
HENRY A. HAMILIN.
